US00D940561S

(12) **United States Design Patent** (10) **Patent No.:** **US D940,561 S**
(45) **Date of Patent:** **** Jan. 11, 2022**

(54) **FLASK**

(71) Applicant: **GUERLAIN**, Paris (FR)

(72) Inventor: **Sébastien Servaire**, Paris (FR)

(73) Assignee: **GUERLAIN**, Paris (FR)

(**) Term: **15 Years**

(21) Appl. No.: **29/718,854**

(22) Filed: **Dec. 30, 2019**

(30) **Foreign Application Priority Data**

Jul. 3, 2019 (EM) 006612685-0001

(57) **CLAIM**

The ornamental design for a flask, as shown and described.

DESCRIPTION

FIG. 1 is a top-front-right perspective view of a flask, showing the design;

FIG. 2 is a front view of the flask of FIG. 1;

FIG. 3 is a rear view of the flask of FIG. 1;

FIG. 4 is a right view of the flask of FIG. 1;

FIG. 5 is a left view of the flask of FIG. 1;

FIG. 6 is a top view of the flask of FIG. 1; and,

FIG. 7 is a bottom view of the flask of FIG. 1.

The broken lines in FIG. 7 depict portions of the flask, specifically the underside of the cap, that form no part of the claimed design.

1 Claim, 7 Drawing Sheets
